UNITED STATES PATENT OFFICE

WENDELL P. SIGLER, OF DAYTON, OHIO

ADJUSTABLE STOCKING FORM

Application filed November 1, 1927. Serial No. 230,351.

My invention relates to garment forms, and more particularly, to a stocking stretcher for maintaining the shape and size of hose while drying.

5 In the present invention there is contemplated a light wire form which will hold the hose distended without undue stretching or strain and will permit free circulation of air to effect quick drying. The form is adjustable within limited range, having a slidingly adjustable heel section to accommodate stockings of different sizes and to enable a stocking foot contracted during washing to be extended to the proper size for drying. Means 10 is also provided for varying the width of the leg portion of the form to prevent shrinkage and maintain the proper size and shape. The invention is embodied in forms or stretchers both for full length stockings and for socks or half hose. It is to be understood that the various stretchers will be provided in different sizes, each size being capable of accommodating several different sizes of stockings. The form or stretcher comprises a wire shape 15 contoured to agree with the normal shape of a stocking, but devoid of a heel portion. This wire shape is reinforced by a sliding brace or truss which maintains the contour of the form, upon which the truss or brace wire is 20 slidingly adjustable and carries the adjustable heel section.

The object of the invention is to simplify the structure as well as the means and mode of operation of drying forms or stretchers for stockings, whereby they will not only be cheapened in construction, but will be more efficient in use, positive in operation, uniform in action and adjustment, and unlikely to get out of repair.

25 40 A further object of the invention is to provide a stocking form or stretcher which will be light in weight and, which will comprise a skeleton form permitting free circulation of air to facilitate rapid drying.

45 50 A further object of the invention is to provide a stocking form having an adjustable heel section which may be extended after the stocking is in place upon the form or stretcher in order to distend a shrunken stocking to the proper and normal size.

A further object of the invention is to provide improved means for adjusting the variable heel sections from the top of the form. A further object of the invention is to provide improved bracing and reinforcing means 55 for a skeleton form and provide means for adjusting and expanding the upper portion of the leg.

With the above primary and other incidental objects in view, as will more fully appear 60 in the specification, the invention consists of the features of construction, the parts and combinations thereof, and the mode of operation, or their equivalents, as hereinafter described and set forth in the claims. 65

70 Referring to the drawings wherein are shown the preferred, but obviously not necessarily the only forms of embodiment of the invention, Fig. 1 is a side elevation of a full length form or stretcher for women's stockings showing by dotted lines the relative adjustment of the movable heel section and the reinforcing truss. Fig. 2 is a similar view of a short length form for men's socks or half 75 hose, likewise showing by dotted lines the relative adjustment of the movable heel section and brace or truss which maintains the outline contour of the form. Fig. 3 is a view similar to Fig. 1 illustrating a modified construction. 80

Like parts are indicated by similar characters of reference throughout the several views.

The structure comprises a skeleton form of wire contoured to afford a conventionally shaped leg portion 1 and a foot portion 2. 85 The wire section comprising the outline of this contoured skeleton form is formed into a helical loop or spring turn 3 at the toe of the foot portion and into additional helical turns or loops 4-4 at the upper extremity of the 90 leg portion 1. From the last mentioned turns or coils the extremities of the contour wire extend transversely of the form in inclined relation and are formed at their extremities into eyes 5 slidingly engaging the contour or 95 outline wire at the front and rear of the leg portion. The upper portions of these contour wires are preferably, though not necessarily, bent into a succession of shallow waves or crenate form for the engagement of the trans- 100

verse brace arms 5 in different angular positions. By slidingly adjusting the brace arms 5 upon the upper portions of the outline or contour wires forming the leg portion 1 the 5 upper end of the form or stretcher is contracted or expanded as may be necessary and as indicated by dotted lines in Fig. 1.

The heel section 7 comprises a bight of wire having loops or eyes at its opposite ends slidingly engaging the contour or outline wire of the rear portion of the form or stretcher. This heel bight 7 is slidingly adjustable toward and from the toe portion of the stretcher or form by the to and fro adjustment of a 15 reinforcement truss or brace 8 with which one end of the heel bight 7 is connected. In practice the reinforcement brace 8 and the heel bight 7 are formed from a single length of wire. The truss like brace or reinforcement 20 brace 8 extends angularly in alternating directions from the contour wire at the front of the form or stretcher to that in the rear and is formed into an eye or loop at each angle embracing the outline or contour wires on which such reinforcement brace is slidingly adjustable. The wire form thus described is introduced 25 into the wet stocking with the heel portion 7 and sliding brace in their advanced position. The stocking being somewhat shrunken when 30 wet, particularly in the case of woolen hose, this advancement of the heel bight 7 facilitates the placement of the stocking upon the skeleton form or stretcher. After the stocking is in place the reinforcement brace or 35 truss 8 which is readily accessible from the top of the stocking is drawn upwardly, thereby drawing the heel bight 7 away from the toe of the form and thus extending the foot of the stocking to the desired size. Ordinarily 40 the form will retain its adjustment without locking or fastening means. If desired, however, the undulating or crenate form or crimp in the contour wire at the upper end of the leg portion may be extended to receive the 45 terminal eye or loop of the adjustable brace 8 and thereby yieldingly hold the brace and with it the heel bight 7 in their adjusted positions. By varying the angular relation of the brace arm 5 at the upper end of the form 50 the form may be expanded to stretch the top of the stocking to the desired size.

The skeleton form or stretcher is made from spring wire of non-corrosive or non-rust character or is suitably plated or coated with a 55 rust-resistant coating.

Referring to Fig. 2 which shows a form for socks or half hose, the general construction is similar to that before described, except that the upper portion of the leg of the form is 60 somewhat contracted to accommodate the smaller cuff on the upper end of the sock. In lieu of the truss shaped brace 8 there is shown in Fig. 2 a modification comprising two sliding tie bars 9 and 10 interconnected by longitudinal tie rod 11. These tie bars 9 and 10

and the connecting rod 11 are formed from a single length of wire having formed therein loops or eyes embracing the contour wires of the skeleton form. This brace wire is extended outside the main form to provide the adjustable heel bight 7. This heel bight 7 is 70 slidingly adjustable upon the main form in the same manner as before described. There is provided at 12 upon the contour or outline wire of the main form a stop lug which is engaged by the brace or reinforcement bar 10 at the limit of its downward movement. This stop lug 12, limits the movement of one end of the brace bar 10 only. The other end, of which the heel bight 7 forms a continuation, is 75 free for a further limited movement, during which the reinforcement or brace member is somewhat distorted. The continued movement of the heel bight 7 and end of the brace bar 10 connected therewith tends to contract 80 the foot portion 2 of the skeleton form as shown by dotted lines. This adjustment of the heel bight 7 thus not only shortens the length of the foot of the form, but it also narrows the foot portion 2. The adjustable 85 brace structure and heel bight connected therewith are held in various positions of adjustment by the engagement of the brace bar 9 in succeeding undulations or crimps 13 formed in the leg of the form. At the upper 90 ends the outline or contour wires are bent inwardly toward each other and are together formed into an involute hook 14, by which the form may be conveniently suspended from a line. The square terminal end 15 formed by 95 bending the contour wires inwardly enables the form to be set upright in a slotted rack, the slots of which receive the square terminal end 15 of the form, in lieu of hanging the form upon a drying line. the bight 7 is preferably an integral extension having eyes enclosing and sliding upon the contour wire of the main frame. Thus by pulling upwardly or pushing downwardly upon the rod 16 which is provided at its upper end with a finger ring 17 for this purpose, the heel 7 is slidingly adjusted to different positions upon the main frame. The main frame is provided with transverse brace arms 18 fixedly connected to the marginal or contour wire at one side of the frame and having loops or eyes 19 slidingly engaging the contour wire at the opposite side of the frame. These brace arms 18 extend through eyes or loops 20 formed at spaced intervals in the adjusting rod 16. Thus upon reciprocation of the adjusting rod 16 to shift the heel bight 7 the brace arms 18 are simultaneously flexed. By their change of position to different angular relations with the main frame they contract or extend the marginal or contour wires of the main frame as shown by dotted lines in Fig. 3. The reciprocatory adjusting rod 16 and its interconnected heel portion 7 and brace arms 18 may be held in various positions of adjustment by the engagement of one of the brace arms in successive undulations or crimps of the main frame wire. While the several forms of stretcher vary as to structural details, it is to be noted that in each form the heel is slidably adjustable toward and from the toe by an operating device extending above the upper end of the stocking to enable it to be extended after the stocking is in place and means is also provided in each instance for spreading the leg portion. The skeleton form permits free circulation of air and induces quick drying.

From the above description it will be apparent that there is thus provided a device of the character described, possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features it is to be understood that the invention is not limited to the specific details shown, but that the means and construction herein disclosed comprises the preferred form of several modes of putting the invention into effect and the invention is therefore claimed in any of its forms or modifications within the legitimate and valid scope of the appended claims.

Having thus described my invention, I claim:

1. In a stocking form of the character described, a skeleton frame of flexible material, including a leg portion and a foot portion, a slidably adjustable heel portion, and an adjustable brace member for the skeleton

form by which the adjustable heel portion is carried, said brace being accessible from the top of the stocking to effect the adjustment of the heel portion within the stocking.

2. In a stocking form, a wire skeleton frame contoured to the approximate conventional shape of a stocking, an adjustable heel portion and an adjusting member slidingly engaged upon the leg portion of the form and accessible from the top of the stocking when on the form for shifting the adjustable heel portion.

3. In a stocking form, a wire skeleton frame, contoured to the approximate conventional shape of a stocking, and transversely arranged adjustable brace members having longitudinal sliding engagement on the frame wire by which the form may be spread or contracted.

4. In a stocking form a wire skeleton frame contoured to the approximate conventional shape of a stocking, the upper ends of the front and rear outline wires being crimped, and brace wires arranged in transverse relation and adjustably engaged with the crimped portion of the outline wires to serve as spreaders by the adjustment of which the form may be expanded and contracted.

5. In a stocking form, a skeleton frame of flexible material contoured to the approximate conventional shape of a stocking, and adjustable brace means slidably adjustable longitudinally of the frame extending transversely between the front and rear marginal portions of the form by the adjustment of which the leg portion of the form may be expanded or contracted.

6. In a stocking form a wire skeleton frame contoured to the approximate conventional shape of a stocking, and a plurality of transverse brace wires slidingly engaged with the front and rear frame wires of the form interiorly of a stocking supported on said form, and capable of movement longitudinally of such frame wires but independent thereof to effect adjustment of such front and rear frame wires toward and from each other without longitudinal change of relation thereof.

7. In a stocking form a wire skeleton frame contoured to the approximate conventional shape of a stocking, and a plurality of interconnected transverse brace wires slidingly engaged with the front and rear marginal wires of the form.

8. In a stocking form a wire skeleton frame contoured to the approximate conventional shape of a stocking, and a plurality of transversely disposed slidably adjustable brace wires interconnecting the front and rear marginal wires of the form interiorly of a stocking mounted thereon at spaced intervals throughout the length of the form.

9. In a stocking form a wire skeleton frame contoured to the approximate conventional shape of a stocking, and a wire bight exteriorly of said frame and slidingly engaged therewith forming an adjustable heel portion.
  - 5
10. In a stocking form a wire skeleton frame contoured to the approximate conventional shape of a stocking, a wire bight, slidingly engaged with the frame and extending exteriorly thereof to form a heel portion and means for securing the sliding wire bight in different positions of adjustment.
  - 10
11. In a stocking form a wire skeleton frame contoured to the approximate conventional shape of a stocking, a wire bight slidingly engaged with the frame and extending exteriorly thereof to form a heel portion and adjusting means for said sliding wire bight
  - 15
- 20
- extending in the plane of the frame to a point adjacent the top thereof and accessible from the top of a stocking upon the form.
  - 20
12. In a stocking form, a flexible leg and foot frame, an independently formed adjustable heel section carried thereby and adjusting means for simultaneously shifting said heel section relative to the leg and foot frame and contracting the foot portion.
  - 25
13. In a stocking form, a flexible leg and foot frame, an adjustable heel section carried by the foot portion, a transverse brace arm for said frame connected with the heel section and means for angularly changing the relation of the brace arm to effect a contraction of the frame with the movement of the heel section.
  - 30
14. In a stocking form, a flexible leg and foot frame, an adjustable heel section, a slidingly adjustable brace arm for said frame, with which the heel section is interconnected, a stop for one end of the brace arm, the other end of which is permitted a further movement to vary the angular relation of the brace arm to the frame and thereby effect a contraction of the frame simultaneously with the adjustment of the heel section.

- 45

In testimony whereof, I have hereunto set my hand this 21 day of October A. D. 1927.

WENDELL P. SIGLER.
